UNITED STATES PATENT OFFICE.

JOHN H. BEERY, OF SPRINGFIELD, OHIO, ASSIGNOR OF ONE-HALF TO
JAMES M. ANTHONY, OF SAME PLACE.

MACHINE FOR APPLYING STRIPS TO PAPER BOXES.

SPECIFICATION forming part of Letters Patent No. 516,983, dated March 20, 1894.

Application filed October 29, 1892. Serial No. 450,410. (No model.)

To all whom it may concern:

Be it known that I, JOHN H. BEERY, a citizen of the United States, residing at Springfield, in the county of Clarke and State of Ohio, 5 have invented certain new and useful Improvements in Machines for Applying Strips to Paper Boxes, of which the following is a specification.

My invention relates to improvement in machines for applying strips to paper boxes, and the especial object of my invention is to provide a box stripping machine especially adapted for use in the manufacture of paper boxes or for similar purposes.

15 My invention consists in the various constructions and combinations of parts herein-after described and pointed out in the claims.

In the accompanying drawings Figure 1 is a plan view of a machine embodying my invention. Fig. 2 is a sectional view of the same, taken on line X X in Fig. 1. Fig. 3 is a detail view of one of the rolls and its bearings. Fig. 4 is a front elevation of the machine. Fig. 5 is a detail view of the paper 25 supporting roll. Figs. 6 and 7 are details of the adjustable head used in connection with the supporting block.

Like parts are represented by similar letters of reference in the several views.

30 In the said drawings A A, represents the main frame, which consists essentially of side pieces A' A'', connected together at suitable intervals by connecting rods a. Extending transversely across the frame are the pasting 35 rolls B B', each of which is arranged immediately above the paste or glue pan C C', so that the lower periphery of said roll extends into said pan. These paste or glue pans C C', are each preferably formed with a lower compartment b b', to which steam is admitted 40 through a pipe c, which leads into the compartment b and thence to compartment b', through a pipe c', and is discharged through pipe c'', so that a circulation of live steam can 45 be secured to keep the glue or paste hot in the pans C C'. Located between the respective paste rolls B B', is a supporting roll B'', and in front of and below the roll B', is also a supporting roll B''. At each side of the 50 main frame near the front are two upwardly projecting standards D D, connected at the

top by a suitable connecting rod d, and provided at intervals with suitable bearings for a supporting roll B⁴; and in front of said standards and substantially on a level with the roll B⁴, is another supporting roll B⁵. Each of the rolls thus described is preferably provided at each end with a cone-shaped bearing point e, adapted to fit in a cone-shaped opening in the end of a screw-threaded rod e', which extends through a suitable opening in the main frame, and is further provided with a lock or jam-nut e'', means being furnished by which all lost motion in the said rolls may be thus taken up and a suitable amount of friction be applied thereto to furnish the necessary tension to the rolls in their operation, as will more fully hereinafter appear. At the rear of the machine and back of the first pasting roll B, is a rod or shaft f, 70 which carries a paper reel E, a similar shaft and reel E', being located behind and below the auxiliary pasting roll B'.

At the front of the main frame is a transverse bar g, which carries a steel plate g', the top of which is substantially on a level with the bottom of the roll B⁵. Extending transversely across the frame and supported in suitable brackets at each end by said frame above and slightly in front of the bar g', is a rod h, which carries a traveling frame h'. In this frame is journaled a revolving knife h², which is so arranged that as the frame h', is moved laterally across the machine on the rod h, the knife is revolved in contact with the steel plate g', and thus forms a cutter to sever the paper which comes over the pasting rolls and through the machine, as will more fully appear hereinafter. On each side of the main frame and projecting laterally therefrom, on the outside of the respective side pieces, and also centrally from the bottom of the frame near the front, is a screw-threaded stud k, having a hand or thumb-nut k', said stud being adapted to receive an adjustable 90 projecting arm F, having a slotted opening l, adapted to fit over said stud and by means of which the said arm may be adjusted to any desired position and be held in the proper position of adjustment by the thumb-nut k'. 100 This arm F, is perforated at its outer extremity to receive a rod or shaft F', which extends

laterally through the end of the arm F, and is adapted to be held in any desired position of adjustment therein by a hand-screw l'. Journaled loosely on the outer end of the rod 5 F', is a bearing plate l', to which is secured a supporting block F², the block being rigidly secured to said bearing plate in any suitable manner so as to turn freely on the rod or shaft F'.

10 The operation of the device as thus described is as follows: A strip of paper from the reel e, is passed over the pasting roll, thence under the supporting roll B², and over the auxiliary pasting roll B', under the supporting roll B³, and over the supporting roll B⁴, in the frame D, thence under the supporting roll B⁵, and over the plate g', which forms the ledger bar for the cutter h². The block F², is adapted to receive the box or other article to which the paper is to be applied. The respective rolls being set at the proper tension, the paper is drawn through and passed around the box, the supporting block being turned as desired to accomplish this end.

15 25 When a sufficient quantity of paper is drawn off the paper is severed by the knife h², a new article placed on the revolving support and the operation repeated. In making paper boxes it is frequently desirable that the edges 30 or corners of the box be covered with a different character of paper or material. To accomplish this a strip of paper from the second reel E', is carried over the auxiliary pasting roll B', prior to the passage of the paper 35 from the main reel E, the main strip being adapted to overlap slightly the auxiliary strip from the reel E', the strips being thus glued or pasted together as they pass over the auxiliary pasting roll, the main strip having already 40 received the glue or paste for this purpose from the main pasting roll B. From this point forward the respective strips are passed in one strip and placed directly on the box or other article, thus applying the two strips 45 to the box or other article at one operation. Any number of strips may be thus applied by placing different reels on the supporting shafts f f', and placing the strips so that they will overlap in the manner described.

50 55 Any desired means may be employed for revolving the cutter h². In that form which I have shown I preferably employ a cord or cable m, attached at each end to the side brackets which support the supporting shaft h, and pass over suitable supporting pulleys m' m² on the frame h', and thence downwardly over a sheave or pulley m³, on the spindle of the cutter h². The cord or cable being stationary the cutter is caused to revolve as it 60 traverses the shaft h, by the passage of the cord around the respective pulleys.

For covering the tops of boxes and similar articles I place the arm F, on the bottom stud k', and provide for the outer extremity a standard n, having at the top a stationary head n', in which is journaled a sliding head n², with the face plate n³, adapted to receive

and hold the supporting block F². This sliding head n², is adapted to be adjusted in the stationary head n', by a screw-threaded shaft 70 n⁴, journaled at each end in the stationary head n', and screw-threaded in the sliding head n². By this operation the block, to receive the work to be operated on, may be adjusted to any desired position to properly receive the paper, after which it may be adjusted to or from the cutting knife, in order that the paper may be severed at the proper point to secure the margin desired, by adjusting the block back or forth by the adjusting screw n⁵. The supporting roll B⁴, as before described, is adapted to be adjusted to different heights in the frame D, a tension screw e', and locking nut e², being provided at each adjustment to secure the proper tension on said roll, the said roll B⁴, being adjusted up or down to secure the proper length of paper through the machine, to more or less dry the glue or other adhesive material which is applied to the work in hand. This roll B⁴, is 85 formed with a ringed or grooved periphery preferably of parallel V-shaped grooves, so as to form knife edged bearing rings which come in contact with the glued or pasted surface of the paper, and thus support the same 90 without removing the adhesive material; these rings also serve the purpose of guiding the paper and preventing lateral movement as the same is drawn through the machine.

A machine as thus described is capable of 100 use in all the operations necessary in making paper boxes or similar articles. By the use of the auxiliary pasting roll means are provided by which the paste is more evenly distributed on the main strip, while at the same 105 time its employment makes it possible to use two or more strips in covering the box or other article, which strips are glued together in their proper positions as they emerge from the machine. By the use of the tension devices, as described, to each of the rolls, means are provided by which the passage of the paper through the machine may be perfectly adjusted and the tension applied thereto at the proper point, so that by loosening the tension 110 of the main pasting roll and tightening that of the auxiliary roll and the supporting rolls, the distribution of the paste or glue by the auxiliary roll may be varied, as desired.

Having thus described my invention, I 115 claim—

1. In a pasting machine having the pasting and supporting rolls, as described, the main frame having on opposite sides thereof, supporting studs for an adjustable arm which carries an adjustable movable supporting block, and a central projecting stud at the bottom of said frame on which said arm may be supported, substantially as specified.

2. In a pasting machine, having the pasting and supporting rolls, as described, an adjustable arm having thereon an adjustable movable supporting block, and fastening devices at the side and at the bottom of said frame

adapted to receive and retain said supporting arm, substantially as and for the purpose specified.

3. In a pasting machine, the combination with the main frame and the pasting rolls therein, supporting rolls to receive the stock after it passes over the said pasting rolls, and a grooved adjustable supporting roll intermediate of the remaining supporting rolls, a traveling knife in front of said supporting rolls, a revolving block in front of said knife,

an adjustable arm for supporting said block, and means, substantially as described, for connecting said arm at the side or bottom of the machine, substantially as and for the purpose specified. 15

In testimony whereof I have hereunto set my hand this 24th day of October, A. D. 1892.

JOHN H. BEERY.
